UNITED STATES PATENT OFFICE.

OSCAR P. MORRISON, OF MAUD, TEXAS.

RAIL-TIE PLATE.

1,099,929.

Specification of Letters Patent. Patented June 16, 1914.

Application filed January 28, 1914. Serial No. 815,042.

To all whom it may concern:

Be it known that I, OSCAR P. MORRISON, a citizen of the United States, residing at Maud, in the county of Bowie and State of Texas, have invented a new and useful Rail-Tie Plate, of which the following is a specification.

This invention relates to improvements in rail tie plates and more particularly to a tie plate which in addition to securing a rail thereto will slidably support the switch point.

An object of the present invention is to provide a rail tie plate with a horizontally extending member which will slidably support a switch point and hold the same in proper relation to the main rail and thus prevent the jouncing of the switch point.

A further object is to provide a tie plate with a horizontally extending member which fits through a suitable slot formed in the switch point, thus preventing the switch point from jouncing which results in the eventual destruction thereof. The horizontal member also holds the main rail to the tie plate.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

Figure 1 is a view in perspective of my improved rail tie plate, showing the horizontal member extending through the main rail and switch point which latter have been illustrated in section. Fig. 2 is a cross sectional view thereof. Fig. 3 is a plan view of the rail tie plate.

Referring to the drawings in which similar reference numerals designate corresponding parts throughout the several views, 4 represents a broad flat base which is provided with suitable apertures 5 extending therethrough, through which spikes or allied means may pass for securing the base or plate 4 to the tie. The apertures 5 are located at the four corners of the plate and a

second set of apertures 6 are located in such spaced relation as to provide openings through which spikes may be driven to engage the flange 7 of the main rail. The said rail includes the web 8 and head 9. Upstanding from the plate 4 is a bracket or arm 10 which carries the horizontally extending guide members 11. The guide member 11 extends through a suitable slot 12 in the web of the main rail and aids in securing the rail to the plate 4. A washer 13 is held against the main rail by the cotter pin 14 which tends to prevent the shifting of the rail in an outward direction.

The switch point 15 is provided with the slot 16 extending therethrough and through which extends the horizontal guide member 11. The guide member contacts with the side walls of the slot and prevents the jouncing of the switch point as the wheels pass thereover, thus largely eliminating the chipping and marring of the switch point. The switch point has been recessed as at 17, allowing the switch point to come into contact with the main rail, although it is to be understood that the precise construction of the switch point and main rail may be varied as desired. The upstanding bracket or arm 10 provides a stop against which the switch point moves when in its outermost position, thus properly limiting the motion of the switch point.

The switch point being of considerable length and the arc through which it travels being relatively small, the curved path through which the point will move will not cause the end walls of the slot 16 to bind against the edges of the horizontal guide member 11. From the foregoing it will be apparent that the horizontally extending guide member will guide and brace the switch point in its movements and also will tend to prevent the spreading of the main rail, as well as to bind the same securely to the base plate 4. Also the upstanding bracket 10 provides a stop against which the switch point may move, thus properly limiting the motion thereof.

Having thus fully described my invention, what I claim is:—

1. A rail tie plate including a base, an upstanding bracket carried thereby, a horizontal guide member carried by said bracket spaced above and extending parallel to the said base, a main rail positioned upon the said base plate with the horizontal member

supported thereby, and a switch point provided with a slot extending therethrough slidably mounted upon said base plate with the horizontal guide member extending 5 through and contacting with the side walls of said slot for the guidance and bracing of the switch point.

2. The combination with a main rail and switch point, of a rail tie plate including a 10 base, an upstanding bracket, a horizontally extending guide member carried by said bracket, said main rail and switch point provided with slots extending therethrough, receiving the horizontal guide member there-

through, means for rigidly securing the main rail to the said tie plate, and means carried by the horizontal guide member preventing the outward movement of the main rail, the said upstanding bracket providing a stop for the movement of the switch point 20 in one direction.

In testimony that I claim the foregoing as my own, I have hereto affixed my signature in the presence of two witnesses.

OSCAR P. MORRISON.
